UNITED STATES PATENT OFFICE

149,571

DESIGN FOR A FOB PIN

George J. Lederer, Providence, R. I.

Application March 18, 1947, Serial No. 137,717

Term of patent 3½ years

(Cl. D45—19)

To all whom it may concern:

Be it known that I, George J. Lederer, a citizen of the United States, residing at Providence, in the county of Providence and State of Rhode Island, have invented a new, original, and ornamental Design for a Fob Pin, of which the following is a specification, reference being had to the accompanying drawing, forming part thereof.

Fig. 1 is a plan view of a fob pin, showing my new design; and

Fig. 2 is a side view of the same.

I claim:

The ornamental design for a fob pin, as shown.

GEORGE J. LEDERER.
